UNITED STATES PATENT OFFICE

2,158,861

VISOR FOR COLLAPSIBLE CAPS

Milton Meyer, Brooklyn, N. Y.

Application September 2, 1937, Serial No. 162,140

3 Claims. (Cl. 2—195)

This invention relates generally to visors for collapsible caps, but more specifically to the means of attachment of a visor to any collapsible cap whereby the visor assumes a flat position when the cap is collapsed and a curved position along the two axes thereof when the cap is in open position.

The main object of the invention resides in the provision of attaching a flexible visor to a collapsible cap of any material whereby when the cap is in collapsed position, the visor assumes a corresponding flat shape, while when the collapsible cap is in open and wearing position, the visor assumes a shape which is curved along the two axes thereof.

Another object of the invention resides in the provision of a flexible visor for attachment to a collapsible cap so that the latter may afford means of shading to the eyes of the wearer.

Another object of the invention is to retain all the features of any collapsible cap and at the same time provide the same with the added element of any type of flexible visor which assumes a flattened position when the cap is collapsed and a curved position along two axes when the cap is opened.

These objects and other incidental ends and advantages of the invention will hereinafter appear in the progress of the disclosure and as pointed out in the appended claims.

Accompanying this specification are drawings showing preferred forms of the invention and wherein corresponding reference characters designate corresponding parts throughout the several views, and wherein:

Figure 1 is a side elevation partly in section of any known collapsible cap showing one form of visor attached thereto, the cap being shown in folded or collapsed condition.

Figure 2 is a top plan view of the cap and visor in unfolded or open position.

Figure 3 is a transverse sectional view of Figure 2 along the plane 3—3 thereof.

Figure 4 is a transverse sectional view of Figure 2 through the planes 4—4 thereof.

Figure 5 is a sectional view of Figure 2 through the plane 5—5 thereof.

Figure 6 is a side elevation partly in section of a special form of visor secured to the collapsible cap shown in Figures 1 to 5.

Figure 7 is a transverse section of Figure 6 through the plane 7—7 thereof.

Figure 8 is a transverse section of Figure 6 through the plane 8—8 thereof.

Figure 9 is a front view partly broken away

showing a visor secured to another form of a collapsible cap.

Figure 10 is a transverse sectional view of Figure 9 through the plane 10—10 thereof.

In accordance with the invention and in accordance with the preferred forms thereof shown in the drawings, visors 20, 21 and 22 are adapted to be secured to any kind of a cap having a collapsible band member and a turned in reinforcing strip at the lower edge thereof, the said visor being flexible and secured along the upper edge thereof inwardly of the ends of the said reinforcing strip, the intermediate portion of the reinforcing strip beyond the upper edge of the visor being secured to the band member. Visors 20, 21 and 22 as shown in the drawings, are preferably crescent shaped as shown in Figures 1, 2, 6 and 9.

Figures 1 to 8 inclusive, show visors 20 and 21 as applied to a special form of collapsible cap described and embodied in United States Patent #1,926,912, dated September 12, 1933. This collapsible cap has a collapsible band member 10 of suitable diameter to fit around the head of the wearer, the lower edge of this band member being turned inwardly to form a reinforcing strip. The band member 10 is provided with two end flaps 12 and upwardly extending front and rear flaps 13 which are turned inwardly from the respective upper edges of band member 10 and pasted to the inner ends of the flaps 12 and to one another. End flaps 12 join the sides of body portion 10 along fold lines 14 which converge to points 15 at the ends of the cap, the central longitudinal elongation thus produced in the top of the cap bringing it into conformity with the curvature of the wearer's head and thus enabling the top of the cap to accommodate itself to the shape of the wearer's head. When the cap is collapsed or folded, it will have the appearance shown in Figures 1 and 6, one side being flattened against the other side and the top of the cap lying closely at one side of the band member 10 and being connected thereto by the fold line 16.

The invention hereinafter to be described is readily applicable to any other type of collapsible cap as shown in Figure 9 where the band member is represented by numeral 17, said band member having its upper and lower edges inwardly turned to form strips 18 and 19 respectively and whose edges 23 and 24 are adjustably secured to one another by any means such as buttons 25 and 26 and buttonhole 27.

The invention contemplates means of affixing visors 20, 21 and 22 to the reinforcing strips 11 and 19 whereby the said visors assume a flat

condition when the band members 10 and 24 are collapsed or folded and a curved condition along the two axes of the visors when the band members 10 and 17 are opened for placement 5 on the head.

Visor 20 along the upper edge thereof is provided with a sweat band 28 secured therealong at the lower edge in any suitable fashion such as stitching 29. The upper edge of sweat band 10 28 is secured to the reinforcing strip 11 by any means such as stitching 30, the line of stitching 30 terminating inwardly of the ends of the upper edge of visor 20. The intermediate portion of the reinforcing strip 11 above line of stitching 30 15 is secured to the band member 10 by any means such as rivet 31. The sweat band 28 is folded upon itself at the two terminations of line of stitching 30 as is indicated by numeral 32' in Figure 4. By this system of affixing visor 20 to 20 collapsible band member 10, the visor is flexible inwardly toward the central vertical axis and downwardly along the longitudinal axis when the collapsible band member 10 is put on the head for purposes of wear. On the other hand, the above 25 described means of affixation of the visor to the band member 10 affords a flattening out of visor 28 when the band member 10 is collapsed.

It is, of course, understood that stitching 30 may be substituted by any affixing means such as 30 paste or eyelets 32 shown in phantom on Figure 1. Moreover, eyelet 31 may have substituted therefor any other affixing means such as a plurality of eyelets 33 shown in Figure 9 or paste to prevent the reinforcing strip 11 in the region 35 contiguous to visor 20 from moving outwardly therewith when the visor is grasped on fitting the hat to the head.

In Figures 6, 7 and 8, a visor 21 is shown which eliminates sweat band 28. The upper edge of 40 visor 21 is provided with slits 34 situated inwardly of the ends and proceeding downwardly along the visor. Below the upper edge of visor 21 and inside of the slits 34, the said visor is secured to reinforcing strip 11 by any means such as rivets 45 or eyelets 35. That portion of reinforcing strip 11 intermediate the end eyelets 35 and above the upper edge of visor 21, is secured to band member

10 by any means such as eyelet 36, all as best shown in Figure 6. Where desirable, the upper edge of visor 21 may be provided with a tape 38 secured thereto to act as a sweat band edge. The upper edges of visor 21 on each side of slits 5 34 may similarly be provided with tape 38.

I wish it distinctly understood that the visor may be of any flexible material and that the collapsible cap may similarly be made of any material. Furthermore, it is understood that 10 minor changes and variations in the means of securing the visor to the reinforcing strip of the collapsible band member may be resorted to without departing from the spirit of the invention and without departing from the scope of the ap- 15 pended claims.

I claim:

1. In combination with a cap having a body member collapsible to form two flat sides, the said body member having a turned in reinforcing portion at the lower edge to form an inner hat band member, a flexible visor secured to one of said flat sides at the reinforcing portion, the ends of the said flexible visor being free of the reinforcing portion whereby the said visor becomes flat when the cap is collapsed and curved along the vertical and horizontal axes when the cap is opened.

2. In combination with a cap having a body member collapsible to form two flat sides, the said body member having an inner band member, a flexible visor secured to one of said flat sides at the inner band member, the ends of the visor being free of the said band member whereby the visor becomes flat when the cap is collapsed and curved along the vertical and horizontal axes when the cap is opened.

3. In combination with a cap having a body member collapsible to form two flat sides, a flexible visor secured to one of said flat sides at the 40 inner surface and above the lower edge thereof, the ends of the visor being free whereby the visor becomes flat when the cap is collapsed and curved along the vertical and horizontal axes when the cap is opened.

MILTON MEYER.
